G. J. HENRY, JR.
DIVERTER FOR FLUID STREAMS,
APPLICATION FILED AUG. 22, 1912.

1,114,262.

Patented Oct. 20, 1914.

UNITED STATES PATENT OFFICE.

GEORGE JACKSON HENRY, JR., OF SAN FRANCISCO, CALIFORNIA.

DIVERTER FOR FLUID STREAMS.

1,114,262.

Specification of Letters Patent. Patented Oct. 20, 1914.

Application filed August 22, 1912. Serial No. 716,434.

To all whom it may concern:

Be it known that I, GEORGE J. HENRY, Jr., a citizen of the United States, residing at San Francisco, county of San Francisco, State of California, have invented a new and useful Diverter for Fluid Streams, of which the following is a specification.

Heretofore, it has been customary in operating tangential wheels under fluid, water or gas pressure issuing from a nozzle in the form of a jet against the buckets of said wheels, to regulate the amount of fluid impinging upon the buckets of said wheels by deflecting a greater or less quantity of pressure fluid from the buckets, either by swinging the nozzle from which the water or fluid issues on a pivotal joint so that the stream would come partially or wholly within the range of said buckets and impinge thereon to meet the requirements of the load on the motor wheel at different times, or to interpose after the fluid jet had issued from the stationary nozzle, a deflector or plate which can be swung more or less into the issuing jet before it reaches the buckets of the motor wheel, said plate deflecting from the buckets a greater or less quantity of the issuing fluid jet. Such a device in its general form is well known to the art, and is the subject of a previous patent issued to the writer, and as such is not claimed broadly in the present invention, but in hydro-electric practice, the power being developed by these wheels is frequently very great and the fluid or water pressure issues under a high head, so that the use of a plate for deflecting the jet of water from its normal path causes a great turning moment about the axis on which the deflector may be pivoted. Such turning moment must be overcome by the governor or by the device actuated by hand to shift the deflector partially or wholly into or out of the jet. To counteract this turning moment, the plate is usually given a curved shape, as set forth in my Patent No. 853,787 issued May 14th 1907. It is obvious that in order to accomplish the desired result it is only necessary to divert the jet or portions of the jet through a comparatively small distance in order that the deflected or diverted water should clear the buckets of the wheel. If the water be diverted or deflected downwardly into the pit beneath the

wheel, a disturbance of the otherwise dead water in the tail race takes place, interfering with the normal clearing of the tail race by gravity action on the water, and sometimes piling the water up to a considerable degree. Water so deflected into the wheel pit causes a considerable noise and sometimes even a vibration of the foundations and machinery. My diverter overcomes these objections enabling the jet of issuing water or other fluid to be partially or wholly diverted from its normal path so that such diverted water or fluid will clear the buckets of the motor wheel and at the same time its general direction will not be changed except to a small degree, thus enabling the water to discharge outward in the same general direction through the open portion of the tail race without interfering with the water flowing through the tail race that has been utilized and discharged from the buckets of the motor wheel.

In order to accomplish the counterbalancing of the turning moment I utilize two plates so related that the diverted water after passing over the surface of one plate is received upon the surface of the second plate and diverted back again into a path approximately parallel with its original direction, and where desired, it may, over the surface of one or both of these plates, be given a sidewise direction into two or more elements, and the surfaces of the plates may be so shaped that the water may be forced to "fan" out so that its velocity is largely reduced by friction with the air in order to reduce its energy more rapidly than if the original jet were retained in its integral form.

The surfaces over which the water flows in my diverter may be formed integral with their supporting members or may be separate and bolted thereto, if the fluid has any corrosive or erosive action upon the material used in their structure, making it advisable to replace them without replacing the supporting members, but in ordinary practice I prefer to cast these plates integral with the supporting members.

By referring to the accompanying drawing the form of my improved diverter and its action will be better understood.

Figure 1 illustrates the principle involved in my diverter and counterbalancing of the

device. Fig. 2 is a cross section through one of the preferred forms of diverters illustrating the curved paths over which the diverted jet passes, with the water wheel and nozzle in their usual positions. Fig. 3 is a plan view of Fig. 2. Fig. 4 is a perspective view with one of the side supporting plates removed. Fig. 5 is an end view showing the path of the diverted water where it is desired to divide it into two portions and "fan" it out as it is being discharged from the diverter surface.

The same letters illustrate similar parts throughout all of the figures.

15 A is the receiving surface on which a portion or all of the issuing jet is received and by which surface it is turned partially from its original direction A' into its secondary direction A''. It is then received upon the 20 surface B by which it is again turned into its direction B' substantially parallel with its entry direction A'.

Plates A and B are mounted upon or cast integral with side supporting plates C and 25 D which in turn are mounted upon an appropriate axis E which is provided with suitable levers and connections of well known form to swing the diverter formed of plates A, B, C, and D about the axis E more 30 or less wholly into or out of the issuing jet A'.

On the jet being first received upon the plate A and being diverted thereby from its original direction, there is a turning moment 35 produced about the axis E tending to swing the plate about said axis E in the direction F, and upon the water acting upon the plate B, there is a turning moment produced about the same axis E tending to swing the 40 diverter in the direction G.

J shows the water wheel and K the nozzle.

It will be noticed that these turning moments are opposite in direction and as the plates A and B receive the same quantities 45 of pressure fluid, and turn said pressure fluid through approximately the same angle, said turning moments F. and G. will be substantially equal in magnitude. They will therefore counterbalance each other making 50 the movement of the diverter plate wholly or partially into or out of the fluid jet, with a very much lighter load upon the mechanism for shifting it and therefore enabling the station attendant to easily swing the 55 plate or the automatic governor to easily swing the plate as may be required to compensate for load changes. In practice the shaft upon which the diverter is mounted is connected to any manual or automatic actuating device. Moreover, the fluid discharged in the direction B' will clear the buckets of the motor wheel and discharge freely into the tail race without disturbance in the wheel pit, and without impact on any 60 of the dead water discharged from the buck-

ets of the wheel, thus preventing vibration of the machinery and foundations, and disturbance of the tail water which have been objectionable features in deflectors heretofore.

The discharge surface B I prefer to make 70 partially flattened on its sides and to raise it somewhat in the center as indicated by H in Figs. 4 and 5. This raised portion acts upon the water flowing over the surface of the plate B in the same manner as the wedge or splitter in the well known tangential wheel bucket, dividing the flowing water into two or more portions so that it takes on a side direction. Any stresses introduced 75 into the parts are counterbalanced by these two portions which are diverted equally and opposite to each other in direction from the normal path.

Having thus described my diverter, I 80 claim:

1. In a deflector for fluid streams a primary surface for receiving a fluid jet and changing the direction of flow of the fluid while passing over said surface in combination with a secondary surface for receiving said fluid after its passage over the primary surface and partially or wholly returning the direction of flow to that of the fluid jet. 90

2. In a deflector for interposing in the path of a fluid stream or streams, a plurality of surfaces to receive the flowing fluid, the turning moments of the surfaces wholly or partially neutralizing to reduce the effort necessary to effect movement of the deflector. 95

3. In a fluid stream diverter a multiplicity of surfaces arranged so that the moments of the forces tending to displace them are wholly or in part neutralized. 100

4. In a fluid stream diverter a multiplicity of surfaces arranged so that the moments of the forces tending to displace them are wholly or in part neutralized, so that the force required to move said diverter into or out of the fluid jet, wholly or in part, is 105 reduced.

5. In a stream diverter in combination with a jet nozzle, curved surfaces for receiving all or any part of a fluid jet said surfaces being opposed to each other as to 110 curvature to divert the jet from its original path.

6. In a stream diverter in combination with a fluid jet issuing from a nozzle under pressure, surfaces for receiving all or any part of the fluid jet said surfaces being opposed to each other and for the purpose of diverting the fluid from its issuing path and discharging said fluid approximately parallel to its original direction. 115

7. In a stream diverter for a fluid jet, the combination of a plurality of surfaces supported on a frame, said surfaces being of curved form and co-related so that, upon a fluid jet passing consecutively over them, 120

125

their moments of inertia about the supporting frame, substantially neutralize each other.

8. In a stream diverter, surfaces for diverting a greater or less quantity or all of a fluid jet; mounted on an axis and set so that the turning moments are partially or entirely neutralized and displacing when swung into the fluid jet part or all of it 10 from its original position, but maintaining its general direction over a diverted path.

9. A diverter for fluid streams mounted to move wholly or partly into the path of a fluid jet consisting of a receiving surface of

curved form and a discharging surface of 15 reversed curved form.

10. A diverter for fluid streams comprising a receiving surface and a discharging surface of substantially reversed form, said discharging surface being formed for dividing the discharging fluid into two or more paths. 20
